MATCH IGNITING DEVICE

Harold A. Warren, 522 S. George St., Goldsboro, N.C.

Filed Dec. 28, 1964, Ser. No. 83,184

Term of patent 14 years

(Cl. D81—10)

FIG. 1 is a top plan view of an igniting device for matches showing my new design, a portion being broken away to indicate indeterminate lengths;

FIG. 2 is an elevational view taken from the right side of FIG. 1;

FIG. 3 is a perspective view showing the cocked position thereof;

FIG. 4 is a cross-sectional view thereof taken on line 4-4 of FIG. 1; and

FIG. 5 is a cross-sectional view thereof taken on line 5-5 of FIG. 1.

The broken line representation of a match in FIG. 3 is for the purposes of illustration only.

I claim:

The ornamental design for a match igniting device, as shown and described.
